UNITED STATES PATENT OFFICE.

CHARLES T. DAVIS, OF BROOKLYN, NEW YORK.

PACKAGE FOR FRAGILE TUBES.

1,121,232.

Specification of Letters Patent. Patented Dec. 15, 1914.

Application filed December 18, 1913. Serial No. 807,461.

To all whom it may concern:

Be it known that I, CHARLES T. DAVIS, a citizen of the United States, residing at Brooklyn, in the county of Kings and State 5 of New York, have invented certain new and useful Improvements in Packages for Fragile Tubes, of which the following is a specification.

My invention relates to special packages 10 and particularly to a package adapted to receive fragile tubes of glass or similar material containing medical, surgical or other supplies.

The object of the invention is to provide 15 a cheap and efficient package which will protect such tubes against breakage during transportation or other rough handling to which they are subjected.

In order that the invention may be clearly 20 understood, reference is had to the accompanying drawings, forming part of this specification, and in which,

Figure 1 is a perspective view of my improved package complete, except for the 25 cover, parts being broken away; Fig. 2 is a plan view thereof; Fig. 3 is a perspective view of the protective lining or tube holding element; and, Fig. 4 is a transverse section through the complete package.

Referring to the drawings in detail, the 30 package comprises an outer container or case of a width slightly greater than the diameter of the tubes to be packed and consisting of a body portion 1, a flange portion 2, and a cover 3. This cover is adapted to embrace the flange 2 in the usual manner, with its lower edge resting upon the upper edge or shoulder 1^a of the body portion.

Within the container I arrange a lining 40 or tube holding element which consists of corrugated cardboard bent and arranged in a novel manner. This board, as clearly shown in Fig. 3, consists of a backing 4 and a fluted or corrugated sheet 5, secured to 45 such backing in the usual or any desired manner. In forming my improved lining, I take a section of such corrugated board and crease or score it along two parallel lines 6 and 7, extending transversely of the corrugations and spaced apart a distance approximately equal to the diameter of the tubes to be packed. I then bend the board into the configuration shown in Fig. 3 so as to form a central portion 8 and side portions

9 and 10. The board thus bent is inserted 55 into the case or container, as clearly illustrated in Figs. 1 and 4, in such manner that the portion 8 is disposed along the bottom of the container while the portions 9 and 10 lie along the sides thereof, with the corrugations 5 extending vertically.

By virtue of the fact that the sides 9 and 10 are integral with each other, the corrugations necessarily lie exactly opposite each other so as to form grooves or pockets for 65 the reception of the tubes. In other words, a projection on the part 9 is opposite a projection on the part 10, and a depression on the part 9 is opposite a similar depression on the part 10, so that a series of parallel 70 pockets is formed as clearly shown in Fig. 2. The tubes are designated by the reference character 11 and snugly fit into the above mentioned pockets, the lower ends of the tubes resting upon the portion 8 of the lining, which forms a cushion therefor, and the upper ends of the tubes being spaced from and protected by the cover 3. The corrugations 5 are preferably of substantially the 75 same curvature as the tubes, but it is obvious 80 that the corrugations could be of somewhat sharper configuration. It will be understood that the tubes are slid endwise into the pockets and are held therein by friction.

In the drawings the package is shown as 85 of a size to hold a dozen tubes, but, of course, may be made to contain any desired number. I am aware that it has heretofore been proposed to protect fragile tubes and the like by means of corrugated board, but where 90 separate pieces of board are employed for the two sides of the container it is very difficult if not impossible to arrange the corrugations exactly opposite each other. By my improved construction, wherein but a single 95 piece of board, bent as described, is employed for both sides of the container, perfect alignment of the corrugations is secured.

What I claim is:

A package for fragile tubes and the like 100 comprising an outer container of a width slightly greater than the diameter of the tubes to be packed, and a lining comprising a piece of corrugated board creased and bent near its middle along two parallel lines running transversely of the corrugations and spaced apart a distance substantially equal 105 to the distance between adjacent corruga-

tions, thus forming an intermediate and two end portions, the end portions of said board being of less length than such tubes, and lying along the sides of the container with the corrugations disposed opposite to and parallel with each other and forming substantially circular open-ended pockets into which the tubes may be inserted endwise,

and with which the tubes engage at a plurality of points on each side.

In testimony whereof I have affixed my signature, in presence of two witnesses.

CHARLES T. DAVIS.
